WINDOW LIFTING AND LOWERING DEVICE
FOR MOTOR VEHICLES

Walter S. Wiseman, Detroit, Mich., assignor of fifteen per cent to Joseph P. Aubin and fifteen per cent to Ernest M. Zahn, both of Detroit, Mich.

Application April 10, 1944, Serial No. 530,283

4 Claims. (Cl. 268—124)

1

This invention relates to new and useful improvements in window lifting and lowering devices for motor vehicles.

The primary object of this invention is to provide a window lifting and lowering device in which the operating parts are contained in an oil tight casing located within the confines of the vehicle door so that said lifting and lowering device will be wholly within the normal contour thereof.

Another object of the invention is to provide a window lifting and lowering device in which the operating parts will be constantly lubricated in a bath of oil contained in said casing so that they will withstand considerable wear and permit the easy and frequent raising and lowering of the vehicle windows.

Another object of the invention is to provide a window lifting and lowering device capable of being easily and quickly installed as a unit in a motor vehicle door frame of conventional and standard form without requiring the use of additional linkage for moving the window.

Another object of the invention is to provide a window lifting and lowering unit which may be easily and readily installed in a motor vehicle door structure by being inserted through a relatively small opening therein and fastened in place on the inner wall of the door structure so that it is only necessary to make a single connection with the window lifting and lowering linkage already installed in the door structure.

Other objects and advantages will become apparent during the course of the following description of the accompanying drawing, wherein:

Figure 1 is an elevational view of a vehicle door illustrating the manner in which the invention is applied thereto;

Figure 2 is an enlarged vertical sectional view of the window lifting and lowering mechanism showing the various parts in detail and illustrating the manner in which the casing is fastened and supported within the confines of a vehicle door;

Figure 3 is a vertical cross-sectional view of the unit casing taken on line 3—3 in Figure 2 and looking in the direction of the arrows to illustrate the concealed parts of the unit and the arrangement thereof;

Figure 4 is a horizontal cross sectional view taken on line 4—4 in Figure 2 looking in the direction of the arrows illustrating the manner in which the driving motor is attached to the window lifting and lowering unit casing; and

Figure 5 is a horizontal cross-sectional view of

the unit casing taken on line 5—5 of Figure 2 illustrating the sliding cross-head and its position within said casing.

In the drawing there is shown an embodiment 5 of the invention as being installed in a vehicle door of conventional design and generally designated by the reference character 5. The door is shown as having a glass window 6 slidably mounted for vertical movement between a pair 10 of vertical guide channels 7 secured to the door structure 5. Secured to the lower edge of the window is a horizontal channel 8 having a pair of lugs 9 depending therefrom at each end thereof. Within each of the lugs is a horizontal slot 10 in each of which is a pin 11 extending from each of the crossed links 12 and 13 which are pivoted as at 14. The lower ends of the links 12 and 13 are pivotally connected to lugs 15 and 16 respectively projecting from the lower ends of 15 the guide channels 7 in opposed relation one to the other. A pin 18 is provided for connecting the lower end of the link 12 to the lug 15 while a pin 18 is secured to the link 13 for operatively 20 connecting the lower end of the link 12 to the lug 15 while a pin 18 is secured to the link 13 for operatively engaging within a slot 19 in said lug 18.

From the above description of the door and window structure it will be readily observed that a vertical upward force applied to the link 12 will cause said glass window 6 to be raised. Similarly, a vertical downward force will cause said 25 window to be lowered into said door between the guide channels 7. As the link 12 is pivoted about its pivot pin 11, the pins 11 and 18 slide in their respective slots 10 and 19, thereby permitting free and easy movement of the window 6.

The door structure includes a pair of inner 30 and outer spaced panel members 20 and 21 respectively, connected at their lower ends by a foot portion 22 so as to provide a closed chamber 23 between the panels for permitting the vertical sliding movement of the glass window 6. Formed in the inner panel member 20 adjacent the lower end of the door structure is an inspection and access opening 24 of adequate size and 35 dimensions to allow the insertion of the window lifting and lowering mechanism about to be described.

The window lifting and lowering unit comprises a casing generally designated by the reference character 25 and said casing is formed 40 of casing sections 26 and 27 having complementary lugs 28 at the sides thereof and complementary lugs 30 at the lower ends thereof for being held together by fastening bolts or the like as at 31. Secured to the casing section 27 is a 45 supporting bracket 32 fastened in place by ma-

chine screws as at 33 anchored in threaded openings 34 in the side wall of said casing section. The ends of the supporting bracket are offset as at 35 and 36 to permit said bracket and unit casing to be inserted through said opening 24 thereof and removably affixed to the inner wall of the panel 20 by threaded fasteners 27 such as bolts and nuts which are adapted to clampingly secure the offset ends of the bracket in position with the offset upper end of the bracket fastened above the opening 24 and the lower offset end of the bracket fastened below said openings (Figure 2).

Each casing section includes front, back, side and end walls 38 to 41 respectively with their meeting edges machined or the like to provide an oil tight point therebetween. Each casing section is provided with a pair of guide ways 42 arranged in spaced apart relation adjacent the corners of the side, front and back walls to slidably guide a crosshead 43 to and from its limits of movement within the unit casing 25.

The meeting edges of the casing walls at the uppermost end of said casing are cut away as at 44 to provide semi-circular openings for receiving a bearing bushing 45 and, similarly, the meeting edges of the bottom walls 41 of the casing are cut away to provide semi-circular openings 46 for the reception of a bearing bushing 47 in axial alignment with the bearing bushing 45. Rotatably supported by the bearing bushings 45 and 47 is a feed screw 48 having reduced ends 49 and 50 forming bearing surfaces for being journaled in said bushings 45 and 47 respectively. The feed screw 48 is threaded in an opening 52 in the crosshead 43 to feed the same along the guideways 42 upon rotation of the feed screw in either of its two directions of movement.

The lower portion of the back wall 39 of said casing section 27 is provided with an offset housing formation 53 at the ends of which are located bearing bosses 54 and 55 in axial alignment for supporting a drive shaft 56.

The drive shaft 56 is directly connected to a reversible electric motor 57 secured to an offset flange portion 58 of the casing section 27 by means of machine screws or bolts 59 so that the motor will be supported thereon and provide a unitary window lift structure capable of being installed in the motor vehicle door after the door has been hung on the motor vehicle or before the motor vehicle has left the assembly line. Actually, the drive shaft 56 may be in the form of an extension of the armature shaft of the motor 57 with a reduced end portion 60 journaled in the bearing boss 54 and the other end journaled in the bearing boss 55. Formed in the other casing section front walls 38 in opposed relation to the offset casing housing 53 is an arcuately curved casing section 61 for accommodating a worm wheel 62 keyed as by means of a key 63 to the reduced bearing portion 50 of the screw feed shaft 48. The worm wheel 62 is in driving engagement with a worm 64 mounted on or formed integral with the armature shaft extension 56 so that rotation of the armature shaft 56 will rotate the feed screw at a reduced rate of speed and thereby cause said crosshead 43 to be reciprocated within the sectional housing 25.

Secured to and extending upwardly from the cross-head 43 is a pair of parallel slide shafts 65 and 66 having their lower ends reduced as at 67 and 68 respectively for being received in openings 69 and 70 so that the extreme lower ends

thereof may be upset by being riveted as at 71 and 72.

The upper ends of the parallel reciprocating rods 65 and 66 are similarly reduced as at 73 and 74 respectively and said rods are adapted to project through the upper wall 41 of the casing 25 and be guided by guide bushings 75 and 76 inserted in cut away portions 77 and 78 formed in the meeting edges of the casing sections 26 and 27.

Connected to and extending between the upper ends of the rods 65 and 66 is a bridge piece 79 which is held in place by means of riveting or upsetting the ends of said rods as at 80 to thereby provide a substantially rigid connection therebetween.

Secured to the intermediate portion of the bridge piece 79 is a clevis 81 having its bifurcated arms 82 projecting upwardly and spaced apart for the reception of a connecting link 83 by means of a pivotal connection 84. A stud 85 is formed on the clevis 81 and said stud is riveted in place as by being upset as at 86. The upper end of the connecting link 83 is pivotally affixed to the cross lever 12 of the window linkages 12 and 13 to impart a vertical up and down movement thereto.

The casing 25 is filled with a lubricant such as oil or grease to constantly supply the working parts of the window lift with a lubricant so that said parts will be bathed in a lubricant and thus prevented from becoming worn due to friction.

The electric motor is reversible to cause the cross-head 43 to be reciprocated in both of its directions, consequently the reciprocating rods will travel up and down in response to the to and fro movement of the crosshead. Such reciprocating movement will be imparted to the window 6 through the medium of the various connecting links and levers 12, 13, 79 and 83.

After the window lift unit has been installed by being affixed to the inner panel 20 of the door structure, the motor may be electrically connected to the vehicle source of current supply with a suitable reversing switch interposed in the circuit so that the driver may operate the window lift from a remote point such as the dashboard of the vehicle.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A power-driven window regulator for raising and lowering a window pane in a vehicle door opening, comprising a casing support mounted within said door and connected thereto a lubricant-tight enclosed casing mounted on said support and having bearing portions therethrough, a screw shaft rotatably mounted within said casing, an external motor connected to said casing and having a motor shaft entering said casing, speed-reducing mechanism within said casing operatively connecting said motor shaft to said screw shaft, a cross head threadedly connected to said screw shaft, a window pane carrier connected to said window pane and a power-transmitting mechanism extending from said cross head through said bearing portions to said window-pane carrier.

2. A power-driven window regulator for raising and lowering a window pane in a vehicle door open-

ing, comprising a casing support mounted within said door and connected thereto a lubricant-tight enclosed casing mounted on said support and having bearing portions therethrough, a screw shaft rotatably mounted within said casing, an external motor connected to said casing and having a motor shaft entering said casing, speed-reducing mechanism within said casing operatively connecting said motor shaft to said screw shaft, a cross head threadedly connected to said screw shaft, a window pane carrier connected to said window pane, a pair of reciprocal rods extending from said cross-head through said bearing portions, and means for connecting said rods to said window-pane carrier externally of said casing.

3. A power-driven window regulator for raising and lowering a window pane in a vehicle door opening, comprising a casing support mounted within said door and connected thereto a lubricant-tight enclosed casing mounted on said support and having bearing portions therethrough, a screw shaft rotatably mounted within said casing, an external motor connected to said casing and having a motor shaft entering said casing, speed-reducing mechanism within said casing operatively connecting said motor shaft to said screw shaft, elongated guides disposed within said casing on opposite sides of said screw shaft, a cross head threadedly connected to said screw shaft with its opposite ends engaging said guides, a window pane carrier connected to said window-pane and a power-transmitting mechanism extending from said cross-head through said bearing portions to said window-pane carrier.

4. A power-driven window regulator for raising and lowering a window pane in a vehicle door opening, comprising a casing support mounted within said door and connected thereto a lubricant-tight enclosed casing mounted on said support and having bearing portions therethrough, a screw

shaft rotatably mounted within said casing, an external motor connected to said casing and having a motor shaft entering said casing, speed-reducing mechanism within said casing operatively connecting said motor shaft to said screw shaft, elongated guides disposed within said casing on opposite sides of said screw shaft, a cross head threadedly connected to said screw shaft with its opposite ends engaging said guides, a window pane carrier connected to said window-pane, a pair of reciprocal rods extending from said cross head through said bearing portions, and means for connecting said rods to said window-pane carrier externally of said casing, said screw shaft, said guides and said rods being disposed substantially parallel to one another.
